UNITED STATES PATENT OFFICE.

JOHN C. GRIESSEL, OF POTTSVILLE, PENNSYLVANIA, ASSIGNOR OF ONE-HALF TO
WILLIAM F. DOYLE, OF POTTSVILLE, PENNSYLVANIA.

BED-PAN.

1,181,001.

Specification of Letters Patent.

Patented Apr. 25, 1916.

Application filed October 18, 1915. Serial No. 56,540.

To all whom it may concern:

Be it known that I, JOHN C. GRIESSEL, a citizen of the United States, residing at Pottsville, in the county of Schuylkill and 5 State of Pennsylvania, have invented a new and useful Bed-Pan, of which the following is a specification.

The invention relates to an improvement in bed pans, and the object is to provide 10 means so that a pan may be supported along side of a bed, cot or the like, in a position to be used by the occupant or patient of the bed without subjecting the occupant or patient to any inconvenience.

With the bed pans now in general use, it 15 is necessary to insert the bed pan beneath the patient, which is often-times disagreeable and painful to the patient, especially after an operation, when it is best for the 20 patient to remain quiet and for the body to assume as flat a position as possible. The present invention overcomes these objections, as the patient can by lying on one side and projecting the hips a short distance 25 over the side of the bed or cot, bring the rectum into such a position with respect to the pan, that an action of the bowels may be had without soiling the bedding or any discomfort to the patient. Furthermore, the 30 bed pan may be used for operations, syringing, draining, enemas, douching and the like.

A further object of the invention is in the 35 provision of protectors in the form of wa- ter-proof sheeting, which is connected to two of the walls of the bed pan, one of the sheets or protectors being located between the bed or mattress, and the patient, and the other sheet or protector extending over the 40 body of the patient, so that there is no danger of the bedding being soiled in performing the operation, and sufficient room is afforded so that access may be had to the body between the sheets or protectors.

The invention consists of certain novel 45 features of construction and combinations of parts which will be hereinafter described and pointed out in the claims. It is evident that changes in the form, proportion, mate- 50 rial and minor details of construction within the scope of the appended claims, may be made without departing from the spirit or sacrificing any of the advantages of the invention.

In the accompanying drawings:—Figure 55 1 is a vertical sectional view of the invention, showing it applied to a bed; Fig. 2 is a perspective view of the invention, showing the position assumed by the waterproof sheeting when in use; Fig. 3 is a detail sectional view of the pan, on a reduced scale; Fig. 4 is an end view, on a reduced scale, showing the position assumed by the sheets or protectors when used for the purpose of carrying the bed pan; and Fig. 5 is a trans- 60 verse vertical sectional view on a reduced scale of the invention, showing the position assumed by the parts when not in use and for shipping, storage and display.

A, represents the mattress of a bed, and 70 1 the foot post and 2 the head post, of the bed.

B, designates the bed pan, which is com- 75 posed of a bottom 3 and upright sides 4. An upright end 5 is connected to the rear terminals of the sides and bottom, for forming a closure. The forward end of the bottom 3 is curved upwardly as at 6, and the forward ends of the sides 4 are rounded on their lower edges to conform to the curvature of the bottom. The curved construction of the forward end of the bed pan affords an outlet or spout in discharging the 80 contents of the bed pan. A flange 7 is formed on the upper edge of the end 5 and 85 projects outwardly at right angles thereto for forming a handle in emptying the bed pan.

Connected to the sides 4 of the bed pan are sheets or protectors 8, which may be of 90 any suitable waterproof material, such as rubber, oil cloth and the like. The upper edges 9 of the sides 4 are turned inwardly and downwardly for fastening the inner folded edges 10 of the sheets or protectors 95 to the sides 4 of the bed pan. The outer terminals of the sheets or protectors 8 are beveled or tapered as at 11, and round wooden handles 12 are connected to the outer ends of the sheets or protectors. The 100 ends of the sheets or protectors are wrapped around the wooden handles and fastened to the body of the sheets or protectors in any suitable manner, for holding the handles in place.

Located along the longitudinal edges of the bottom 3 and on the lower surface there- 105 of, are straps 13, for the reception of the

angular ends 14 of the guard 15. The guard 15 is constructed preferably from a spring wire or rod, which is bent at its center forming two parallel members 16. The lower 5 portion of the members 16 are straight and engage the outer surface of one of the sides 4. The members are curved or bowed from the upper edge of the side 4, and project across the body of the pan. 10 Each of the sheets or protectors 8 is provided with a transverse strap 17 through which the guard 15 extends for supporting the sheet or protector which goes over the body of the patient, and it also affords a 15 support for the bedding so that it will be held in a position to avoid soiling the same. The guard has its outer end so arranged that it will conform to but will be spaced above the body of the patient, and thereby hold 20 the uppermost sheet of the protector in such position that the hand of the physician or attendant can be inserted between the sheets or protectors for attending to the patient.

When the device or apparatus is not in use 25 the sheets may be rolled on the wood handles and inserted within the bed pan together with the guard 15, as shown in Fig. 5.

The guard can be applied to either side of the bed pan and to either sheet, so that 30 the device can be placed along side of either side of the bed. In some instances, the guard may not be used and especially when the patient needs the assistance of an attendant.

35 The bed pan can be made of various sizes, but generally it will be constructed say about eighteen inches long, four inches wide and four inches deep, and may be made of any suitable material, such as rubber or 40 metal.

When the bed pan has been used, or it is desired to carry the same, the guard is removed, and two sheets are placed together, so that both handles 12 can be grasped in 45 one hand of the attendant, and by grasping the handle 7 in the other hand, as shown in Fig. 4, the contents of the bed pan can be emptied.

It will be seen from the foregoing that I 50 have provided a simple device which can be manufactured at a small cost, and which will be durable and efficient, and possesses great utility for the purposes designed.

When the bed pan is to be used by a patient, one of the sheets is placed over the mattress and beneath the patient so that the body of the patient will hold the pan along the side of the bed, and the other sheet will extend over the body of the patient and the 55 handle thereof grasped by the patient for maintaining the bed pan in proper position along the side of the bed. The guard will support the sheet which extends over the body of the patient, and hold it together 60 with the bedding at an elevation sufficient to

prevent the bedding from being soiled, and the sheet from coming in contact with the patient.

What I claim is:

1. In combination with a bed pan, a flexible waterproof sheet connected to the pan and extending from the upper edge thereof and adapted to be projected laterally therefrom. 70

2. In combination with a bed pan, a flexible waterproof sheet connected to the pan and extending from the upper edge and projecting laterally therefrom, said sheet being placed beneath the patient for supporting the pan along the side of the bed, the flexibility of the sheet permitting the latter to be rolled up and contained within the pan. 75

3. In combination with a bed pan, two flexible waterproof sheets connected to the pan and extending from the upper edge of the same, one of said sheets being placed beneath the patient for supporting the pan along the side of the bed, while the other sheet extends over the body of the patient, the flexibility of the sheets permitting them 80 to be rolled up and contained within the pan when not in use. 85

4. A bed pan comprising sides, a bottom and ends, flexible waterproof sheets connected to the upper edges of the sides and 90 extending therefrom, one of the sheets being placed beneath the patient for supporting the pan along the side of a bed, and the other sheet extending over the body of the patient for protecting the bedding; said sheets having 95 coating handles. 100

5. A bed pan comprising sides, a bottom and ends, flexible waterproof sheets connected to the upper edges of the sides and 105 extending therefrom, one of the sheets being placed beneath the patient for supporting the pan along the side of a bed, and the other sheet extending over the body of the patient, and means connected to the pan for supporting the last mentioned sheet so that 110 the bedding may be protected. 110

6. A bed pan having flexible waterproof sheets extending from the upper edges of the sides, one of said sheets extending over the body of the patient and formed with a handle to be grasped by the hand of the patient for assisting in holding the pan along the side of a bed, and the other sheet being located beneath the body of the patient. 115

7. In combination with a bed pan, a flexible sheet connected to the pan and extending from the upper edge of the same, and a guard connected to the pan and to the sheet for supporting the latter above and out of 120 contact with the body of the patient. 125

8. In combination with a bed pan, a flexible sheet connected to the pan and extending from the upper edge of the same, and a guard connected to the pan and also con- 130

nected to the sheet, both connections being detachable, the sheet being longer than the guard, so that it projects beyond the same and may be grasped by the patient.

- 5 9. A bed pan having flexible waterproof sheets connected to the upper edges of the sides, one of the sheets being received beneath the body of a patient and the other sheet extending over the body, a strap connected to the bottom of the bed pan, a guard having angular ends received between the strap and bottom of the pan for connecting the guard to the bed pan, and a strap on the sheet extending over the body
- 10 15 of the patient through which strap the guard extends for supporting the sheet above the pan and holding the bedding so that it will not be soiled.
10. A bed pan, comprising sides, bottom and ends, flexible waterproof sheets connected to the upper edges of the sides, one

of the sheets being received beneath the body of a patient for holding the bed pan along the side of a bed, and the other sheet extending over the body and grasped by the 25 hand of the patient for holding the pan in position, straps on the bottom of the bed pan, a curved guard having angular ends received in one of the straps of the pan for connecting the guard to the bed pan, and 30 straps on the sheets, said guard being adapted to extend through the strap on one of the sheets for holding the sheet above the patient and maintain the bedding at an elevation so that it will not be soiled. 35

In testimony, that I claim the foregoing as my own, I have hereto affixed my signature in the presence of two witnesses.

JOHN C. GRIESEL.
